HEATING AND VENTILATION OF PAPER-PULP-GRINDING BUILDINGS.

Application filed December 11, 1926. Serial No. 154,295.

This invention relates to paper pulp manufacture. An object of this invention is to produce a process and apparatus for the production of paper in which the pulp is obtained with a minimum of expense for fuel and a minimum of discomfort to the workers. It is a further and more specific object to produce a ground pulp without the presence of an undue humidity or of fog within the building structure, to make provision whereby the power expended in grinding the pulp which appears as heat at the grindstone, is recovered and utilized to condition and warm the air within the building.

The invention accordingly comprises the several steps and the relation and order of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

For a fuller understanding of the nature and objects of the invention reference should be had to the following detailed description taken in connection with the accompanying drawing, in which:

Figure 1 is a cross section of a building structure embodying this invention. Figure 2 is an enlarged sectional view of the grinding machinery. Figure 3 is a top plan view of an entire plant, showing diagrammatically, a practical assembly of a plurality of the apparatus, such as are illustrated in Figures 1 and 2, together with the heat conserving and air conditioning and distributing apparatus. Figure 4 is a vertical section through the apparatus shown in Figure 3.

The grinding of wood into pulp at commercial speeds requires the consumption of so much power that there is generated at the grinding machinery a great amount of heat. This grinding is done under water or in the presence of water and the heat so generated appears in the form of an increase of temperature of the pulp and in the generation of water vapor or low pressure steam. These facts are objectionable for two reasons. First, the emission of so much low pressure steam into the building structure creates a condition of humidity and fog within the structure which is inimical to the health, comfort and efficiency of the employees employed

therein. The amount of this vapor, furthermore, is so great and the structures are frequently of such size that the ordinary systems of ventilation, including the supply of sufficient fresh air to maintain the proper living conditions, would be expensive in operation whenever conditioning of the air was necessary.

The system is, furthermore, objectionable, in that the heat appearing from the grindstones is so great in quantity that its loss is a material factor in the cost of production, moreover the regulation of heat at the grinding stone is a serious limitation on the speed at which the operation can be conducted.

In accordance with this invention a system of air circulation is maintained within the building structure first serving to ventilate the structure and second, passing adjacent to the grinding machinery to lower the temperature thereof and prevent excessive heating. From this point, where the air absorbs the heat and moisture, it is confined out of contact with the air within the room, but it is carried through a heat interchanging apparatus, whereby the greater portion of its contained heat units are utilized to warm the air being brought into the building by the ventilating system. The pulp, after leaving the grinding machinery, may be conducted to a screening apparatus, and if it still retains sufficient temperature, material quantities of low pressure steam will be given off by it. It is within the contemplation of this invention that these heat units shall be utilized together with those from the grinding machinery.

Within the broad scope of this invention it will be obvious that different forms of grinding and screening machinery may be utilized and different methods of ventilation and of heat interchange. In the accompanying drawings I have shown one practical form of such an apparatus which will serve as an illustration of one practical method of carrying out the invention, but obviously, within the broad scope, other forms of apparatus commensurate with the invention claimed, may be employed.

In the drawings, Figure 1 indicates, a building structure in which is housed the grinding machinery shown, generally at 2, the screening machinery indicated, generally, at 3, may be housed in a separate structure but it is here shown enclosed in the same one. The numeral 4 designates the logs to be ground.

In the form of grinding apparatus illustrated, a grindstone 10 is mounted on a suitable shaft 11, which may run longitudinally of the building, as shown in Figure 4, to serve 5 a plurality of grinding apparatus and be driven by a motor 12 at one end thereof. Each of these grindstones is surrounded by a housing 13 carrying a plurality of pockets 14 for the reception of the logs to be ground. 10 Each of these pockets is arranged to have its inner end substantially adjacent to the grindstone, as shown at Fig. 2, while at its outer end it is provided with a follower 15 operated by hydraulic cylinders 16, to exert pressure 15 upon the logs to cause them to bear up against the grindstone.

The lower end of the grindstone operates in a well 17 having at one side a gate 18 over which the pulp may overflow, as water is fed 20 to the well and mingles with the disintegrated fibers. The height of the gate may be varied to control the depth of water in the well.

The housing 13 may be provided, at one 25 side, with an inspection opening 19 to afford access to the grindstone for purposes of inspecting, truing, dressing, or adjusting the stone, while a corresponding opening 20 is arranged opposite the point where the pulp 30 flows over the gate 18, to permit inspection of the pulp as it is discharged from the sump. The inspection opening 20 should be small consistent with the necessity of affording satisfactory inspection of the pulp. A baffle 21 35 is supported by the frame between the discharge of the grindstone and the opening 20, to prevent the splashing of the material from the stone outwardly through the inspection opening. By the arrangement shown the inspection opening 19 is so located that air 40 drawn in through it impinges directly upon the grinding stone thereby greatly assisting in lowering the temperature thereto and permitting the increase of speed of the operation.

45 The form of the parts forming the opening 20, in Fig. 1 are slightly different from that of Fig. 2 as will be seen. The opening may be provided with a flexible coverflap 20'.

As specifically illustrated, a pair of such 50 grinding machines are associated together, discharging the ground pulp into a compartment 22, which compartment, save for its connection to the grinding machinery, is closed against the admission of air. It thus serves to 55 confine the pulp and to convey it to the point of discharge from the grinding machines, and at the same time, it confines the vapor arising from the pulp and the air sucked into the compartment by the ventilating machinery, hereinafter described and to conduct the air and vapor outwardly for ultimate discharge from the compartment.

60 The pulp discharged from the chamber 22 is preferably carried to the screening machinery, which is illustrated at 3 in Figures 3 and

4. To this end the bottom of the compartment 22 is inclined to the left, as seen in Fig. 4, to permit a free flow of the pulp.

The screening machinery comprises a semi-cylindrical screen member 25, into which the 70 pulp is discharged. Above this and co-axial with it is a shaft 26 carrying a plurality of supporting arms 27 which are adapted, by rotation of the shaft, to move across the inner 75 face of the cylindrical screen, continually to bring fresh portions of the pulp into contact with it. A reservoir 28 is provided below the screen to receive the pulp passing through the screen, and is carried thence for use. Any material too coarse to pass through the screen 80 is carried by the beater arms over the edge 29 of the screen, to be discharged into a trough 30 for disposition.

The screening apparatus just described is 85 preferably enclosed by a cover 31 to form a compartment for confining the vapor given off during the screening operation. This compartment serves also as an air duct, which may communicate with the interior of the building structure by an opening, as shown at 90 32, and convey air from the said opening over the grinding machinery, to be ultimately discharged from the building, as will be more fully described hereinafter, thus carrying with it, in its passage, the vapor. This compartment, formed by the cover 31, is conveniently in contact with and may form a continuation of the chamber 22, in so far as air movement is concerned, whereby the air admitted through the opening 32 is discharged 95 from the building through the chamber 22, as will be clear from Fig. 4.

The ventilating apparatus employed in this invention comprises primarily, an air inlet 33 communicating by a conduit 34 with a fan 105 35, and being discharged by the said fan through openings 36 in a fresh air conduit 37. These openings may, if desired, be distributed over the building and are preferably arranged to suit local conditions.

110 The chamber 22 communicates by a conduit 38 with an exhaust fan 39, by which it is forced upwardly and outwardly of a stack 40, which may be conveniently provided with a cowl 41 to prevent the entrance of rain and to 115 assist in the movement of the air through the stack. Means are provided for absorbing as much of the heat as possible from the outgoing air and communicating the same to the incoming air. As illustrated, this is 120 provided by passing both air streams through an economizer, generally indicated at 42. This economizer may conveniently be in the form illustrated in my U. S. Patent 1,514,600, of November 11, 1924, which is a practical apparatus which will effectively carry out the purpose of this invention. This economizer 125 comprises a chamber containing a plurality of corrugated flat tubes extending from one wall of the chamber to another, through 130

which tubes the outgoing air is caused to pass while the incoming air is caused to move on the outside of the tubes transverse to that direction and in intimate contact with them.

5 The absorption of heat from the outgoing air results in the condensation of a portion of the water vapor contained therein, which thus falls to the bottom of the stack 40. This stack is, therefore, preferably provided with 10 a water outlet 43, positioned to drain the water from the bottom of the stack.

It is desirable to provide an auxiliary heater 44 to assist in heating the incoming air, should the recovered heat be insufficient to 15 maintain the proper temperature within the building. This auxiliary heater may conveniently be situated within the conduit 34. A spray 19^a is provided within the inlet 19, which serves the combined function of cooling 20 the grindstone and of furnishing the water necessary to form the pulp. This spray is preferably directed toward the stone.

The operation of the device is as follows:—

The turning of the stones disintegrates the 25 logs into pulp. As will be understood, the grinding of the logs produces vapor, which is confined by the hood 13, by the chamber 22 and stack 40. The exhaust fan 39 maintains a circulation of air through these chambers 30 which prevents the discharge of any of the vapors through the openings 19 or 20, but on the contrary, carries all of the said vapors outwardly, to be discharged through the economizer and stack to the outer air.

35 The fresh air entering through the inlet 33 passes through the economizer, where it absorbs a material portion of the heat contained in the outgoing vapor and air. It is then forced by the fan 35 through the conduit 37 40 to be discharged through the openings 36 thereof. It will thus be seen that the circulation of the air is maintained inwardly at the top of the room through the openings 36 and outwardly at the bottom through the opening 45 32, adjacent to the screening apparatus and through the openings 19 and 20 of the grinding machine, the air thus sucked out carrying with it substantially all of the vapor and at the same time a considerable proportion of 50 the heat is utilized.

With the above construction it will be clear that the temperature within the building becomes automatically, to a large extent, self-regulating. The heat absorbed from the outgoing air and vapors is dependent upon the temperature of the incoming air and increases very rapidly as the temperature of the incoming air decreases. This is due not only to the absorption of sensible heat from the gases, but also to the fact that a larger proportion of the vapors given off condense and give up their latent heat. It results that large changes of temperature of the outside air are not reflected by corresponding changes of internal temperature, even where no auxiliary

heating means are employed. Thus, the apparatus assists in maintaining uniform temperature in the building regardless of external conditions.

Since certain changes in carrying out the 70 above process and in the construction set forth, which embody the invention, may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention 80 herein described, and all statements of the scope of the invention, which, as a matter of language, might be said to fall therebetween.

Having described my invention, what I claim as new and desire to secure by Letters 85 Patent is,

1. The process of manufacturing wood pulp, which comprises disintegrating the wood in a building structure in the presence of water to form a pulp, confining the air adjacent to the grinding machinery and to the pulp into a passageway, exhausting the air from the structure through said passageway, admitting a fresh supply of air to the said room and transferring heat from said exhaust air to said fresh air.

2. The process of ventilating a building structure for the manufacture of wood pulp, which comprises admitting air to the structure from the outside, passing said air from said room to said grinding machinery through the inspection opening to cool the machinery and thereafter exhausting said air out of contact with the air enclosed within the structure.

3. The process of ventilating a building structure for the manufacture of wood pulp, which comprises exhausting the air from said structure and mingling with said exhaust all of the vapors formed in the manufacture of 110 said pulp and utilizing the heat of said vapors to warm incoming air.

4. The process of manufacture of wood pulp, within a building which comprises maintaining a circulation of air from the room toward the generating machinery and from the generating machinery to the outside, whereby the vapors generated are carried outside the building without co-mingling with its contents.

5. The process of manufacture of wood pulp, which comprises grinding the pulp substantially enclosing the atmosphere surrounding said grinding machinery and providing an inspection opening through said enclosure through which the discharged pulp may be inspected and maintaining an outdraft from the room through said inspection opening.

6. A device of the character described comprising in combination mechanism adapted 130

to disintegrate wood into pulp, a housing to confine the air in the immediate vicinity of said machinery, having an opening through which the ground pulp may be inspected, an 5 exhaust fan and conduit connecting the intake of said fan with said housing.

7. The process of ventilating a building for the manufacture of paper pulp which comprises introducing the air into the building 10 and warming said air before introduction to the building from the heat of the grinding and withdrawing the vapor generated by the grinding without co-mingling with the air within the building.

15 8. A device of the character described, in combination, a conduit adapted to be installed to introduce air into a building, a second conduit adapted to be installed for the withdrawal of air from the building and to include pulp making machinery, means for withdrawing air from said second mentioned conduit, said second mentioned conduit having an inlet adapted to receive air from the interior of the building and to project the 20 same on to the pulp-grinding machinery.

25 9. The process of manufacturing wood pulp in a room which comprises grinding the wood in the presence of water to form a pulp, confining the air adjacent to the grinding machinery by a housing and thereby separating it from the air in the room and withdrawing the air and pulp through a common passageway at a rate sufficient to create a partial vacuum within the housing.

30 35 10. The process of manufacturing wood pulp within a room which comprises grinding the wood in a room in the presence of water to form a pulp, carrying off the pulp in a duct, screening the pulp to remove excess 40 moisture, substantially completely surrounding the grinding machinery, the duct and the screening machinery with a housing to separate them from the air in the room and ex

hausting the air from the interior of said duct to form a partial vacuum within said 45 housing thereby inducing the flow of air inwardly into the housing from the room and outwardly from the housing through said duct.

50 11. The process of manufacturing wood pulp within a room which comprises grinding the wood in the presence of water to form a pulp separating the atmosphere immediately surrounding the grinding machinery from the atmosphere in the room by a housing, withdrawing air from said housing at a rate faster than steam is generated by the disintegration and admitting air to the housing at a point to be projected directly upon the grinding stone whereby air is exhausted 55 from the building for ventilating purposes and utilized to cool the grinding stone and serve as a vehicle for carrying off the steam at substantially atmospheric pressure.

60 12. The process of manufacturing wood pulp within a room which comprises grinding the wood in the presence of water to form a pulp separating the atmosphere immediately surrounding the grinding machinery from the atmosphere in the room by a housing, withdrawing air from said housing at a rate faster than steam is generated by the disintegration and admitting air to the housing at a point to be projected directly upon the grinding stone whereby air is exhausted 65 from the building for ventilating purposes and utilized to cool the grinding stone and serve as a vehicle for carrying off the steam at substantially atmospheric pressure. 70

75 13. The process of manufacturing wood pulp within a room which comprises grinding the wood in the presence of water to form a pulp separating the atmosphere immediately surrounding the grinding machinery from the atmosphere in the room by a housing, withdrawing air from said housing at a rate faster than steam is generated by the disintegration and admitting air to the housing at a point to be projected directly upon the grinding stone whereby air is exhausted 80 from the building for ventilating purposes and utilized to cool the grinding stone and serve as a vehicle for carrying off the steam at substantially atmospheric pressure, admitting fresh air to the room and transferring heat from the exhausted air and from the steam carried thereby for warming the air admitted to the room.

In testimony whereof I affix my signature.

EMIL A. BRINER.
